United States Patent Office

Des. 218,867
Patented Sept. 29, 1970

218,867

DISPLAY CASE FOR TOY VEHICLES

Martin I. Sheps, Palos Verdes Peninsula, and Harold E. Steinberg, Culver City, Calif., assignors to Mattel, Inc., Hawthorne, Calif., a corporation of Delaware

Filed May 15, 1969, Ser. No. 17,173

Term of patent 14 years

Int. Cl. D6—01

U.S. Cl. D80—11

FIG. 1

FIG. 3

FIG. 2

FIG. 4

FIG. 1 is an isometric view of a display case for toy vehicles embodying our new design;

FIG. 2 is a side elevational view thereof;

FIG. 3 is a top plan view thereof; and

FIG. 4 is a bottom plan view thereof.

We claim:

The ornamental design for a display case for toy vehicles, as shown.
